ATTORNEY.

UNITED STATES PATENT OFFICE.

FREDERICK L. LINDHORST, OF DETROIT, MICHIGAN, ASSIGNOR TO DETROIT TORCH & MANUFACTURING COMPANY, OF DETROIT, MICHIGAN, A CORPORATION OF MICHIGAN.

FIRE POT.

Application filed November 16, 1921. Serial No. 515,500.

To all whom it may concern:

Be it known that I, FREDERICK L. LINDHORST, a citizen of the United States, residing at Detroit, in the county of Wayne and

5 State of Michigan, have invented certain new and useful Improvements in Fire Pots, of which the following is a specification.

This invention relates to fire-pots and has for its object an improved fire-pot which 10 is provided with an improved arrangement for preheating the fuel oil and concentrating the flame. The same is also provided with an improved grid whereby the burner may be easily disassembled from the other parts.

15 These and other features will be described in the specification following.

In the drawings,—

Fig. 1 is a side elevation of the fire-pot showing a part of the tank broken away.

20 Fig. 2 is a top plan view of the fire-pot with the shield in place.

Fig. 3 is a section on the line 3—3 of Fig. 2, showing a part of the shield.

25 Fig. 4 is a cross section on the line 4—4 of Fig. 1.

Fig. 5 is a view largely in vertical section of what I call the "chimney" and what is ordinarily called the coil cup.

30 *a* designates the fuel tank provided with the usual air pump *b*. This fuel tank has the bottom provided with an annular flange which engages in and is soldered to the beaded flange of the side walls of the tank. At spaced intervals along the two flanges

35 are heavy gauge metal clips *c*. These act as wear pieces and are simply strips of heavy gauge metal that double over the bead formed by the turning of the outer flange over the inner flange as at *d*.

40 Three long studs or posts *e* are threaded at opposite ends and form supports for the usual burner grid *f*. This grid is provided with three integrally cast ribs *g* on which is to set the vessel in which is contained

45 the substance to be melted. The grid is also perforated to receive the studs *h* which are riveted onto the sides of the burner chimney *i*. This burner chimney is secured in depending relation with respect to 50 the grids by slipping the studs up through the perforations and running on the nuts *k*. The cup shaped shield *j* is arranged to be

seated on the outside of the ribs *g* in the customary way so as to protect workmen from splattering of the substance in the vessel in which it is being melted. 55

Heretofore it has been customary to use a coil of tubing in this chimney and hence this chimney has ordinarily been called a coil cup. A burner such as designated *m* 60 has been used at the lower end of the coil and has been provided with the usual small fuel orifices *n* that allows the pressure to project the fuel oil up against the coil. If the flame does not strike directly against 65 some part of the coil the burner will not operate satisfactorily as the necessary pre-heating of the fuel oil will not be secured.

It is the object of the present invention to introduce an improvement over this coil 70 in concentrating the flame and also in pre-heating the fuel oil. This tubing leading to the burner is usually, if not always, provided with a fine wire filter, that is, a mass of fine wires or similar material is secured 75 in the tubing before it is bent to form a filter for the fuel oil. Obviously after this tubing is so filled with the fine wires and is bent in a number of convolutions, it is impossible to remove these wires in case of 80 obstruction. Hence the filter cannot be cleaned. It is the object of my invention to provide a preheating run of tubing of such a character that the wires may be easily drawn out and cleaned when necessary. 85

To this end instead of connecting the usual coil of tubing to the elbow *o*, I provide a short run of tubing which has a sort of bulging elbow or C run at the elbow. The whole preheating tube might be said to 90 resemble, roughly, an interrogation mark. This C portion of the preheating tube is carried out into the axis of the burner barrel or tube *p*. This is a tube very similar to the burner barrel of an ordinary blow torch. 95 It is provided with air admitting holes and at the lower end is provided with a mouth into which is directed the stream of fuel oil from the burner. The upper end of the barrel tapers to concentrate the flame in much the same way as the blow pipe burner shell tapers. However, the barrel when cast is provided with two features not found in the ordinary blow pipe burner shell, namely, a 100

lip *q* (see, in particular, Fig. 4). This is provided with a groove to receive the top run of the $\textcircled{?}$ shaped preheating tube. A similarly grooved clip *r* can be fitted over the top of this $\textcircled{?}$ shaped preheating tube. One side of the burner barrel is indented as at *s* to receive the lower leg of the $\textcircled{?}$ shaped preheating tube and thereby properly locate the burner carried on the end of the tube with respect to the mouth of the burner shell. The burner on the end of the tube is an ordinary form of burner for fire-pots and is simply a closed end short tube *m* with an orifice *n*. This burner screws into the elbow *t* and it may be taken out by unscrewing to permit the preheating member to be removed from the chimney.

It will readily be seen that with only the half convolution contained in this preheating tube it will be easy enough to draw out and replace a mass of filtering wires which cannot be done with the ordinary curled preheating tubing. The **C** portion of the $\textcircled{?}$ shaped preheating tube projects out into the axis of the burner shell and directly above the oil orifice *n* through which the oil is projected under considerable pressure up against the elbow to properly preheat the oil to secure the steady combustion which is necessary for successful operation. Furthermore, the use of the burner shell which acts both as a mixing chamber and combustion chamber very materially aids in consistent and steady operation. The upper portion of the tapering burner shell is the combustion chamber. The lower portion is the mixing chamber where the air mixes with the oil issuing from the orifice *n*. With the elbow of the $\textcircled{?}$ shaped tube coming directly out into the axis of the combustion chamber proper preheating is always assured and a steady flame will be thereby secured. Furthermore, the products of combustion are all concentrated toward the center of the grid so as not to be uselessly dispersed at the sides.

Still another feature is the arrangement to secure ease of disassembly. The grid is solid for about three-quarters of the way around and for the other quarter it has a hinged section *u*, shown in dotted lines in the outer position in Fig. 2. By unscrewing the union nut *v* that connects the oil pipe *w* with the valve coupling *x* and by swinging out the hinged grid section, it is possible to lift the preheating tube and the vertical oil pipe and the connecting elbow directly out of the chimney *i*. Of course, the burner *m* has to first be unscrewed. This swinging section has a portion *y* that is offset lower than the main portion of the segment and is pivoted on one of the posts *e*. The other end of the segment has a section *z* offset on a lower plane and is adapted to hook over the other post when the clamping nut 1 is

released. When the clamping nut is tightened it holds the hinged grid section firmly in place.

What I claim is:

1. In a fire-pot, the combination of a grid, a chimney supported below the grid, a burner shell supported in the chimney, a separate and detachable preliminary heating tube supported in the burner shell, and a burner supported below the burner shell and arranged to project fuel oil into the burner shell. 70 75

2. In a fire-pot, the combination of a grid, a chimney supported below the grid, a preliminary heating tube supported in the chimney, a separate burner shell supported upon the said tube and arranged to concentrate the flame upon a portion of the tube which runs along the center of the shell, and a burner supported by the tube below the burner shell and arranged to project fuel oil up into the burner shell. 80 85

3. In a fire-pot, the combination of a grid, a preliminary heating tube supported below the grid, a separate burner shell supported by the preliminary heating tube below the grid and arranged to concentrate the flame upon a portion of the tube, and a burner supported below the burner shell and arranged to direct a stream of fuel oil up into the burner shell. 90 95

4. In a fire-pot, the combination of a grid, a burner shell provided with a lip extending laterally at its upper end, a preliminary heating tube supported upon said lip and having a part running into the center of the shell, and a burner supported on the lower end of the tube and arranged to direct a stream of fuel up into the burner shell. 100 105

5. In a fire-pot, the combination of a grid, a preliminary heating tube supported under the grid, a burner shell provided with a laterally-extending lip at its upper end for supporting the preliminary heating tube and provided with a dented-out side portion, said preliminary heating tube having a **C** shaped convolution running into the center of the burner shell and then running into the dented-out portion of the side walls of the shell, and a burner supported on the lower end of the tube and having an orifice directing a stream of fuel oil up into the burner shell. 110 115

6. In a fire-pot, the combination of a grid, a preliminary heating tube having a portion formed into a $\textcircled{?}$ shaped run of tubing, a burner shell supported about such run of tube, and a burner arranged below the shell and arranged to direct a stream of fuel oil up into the shell. 120 125

7. In a fire-pot, the combination of a grid, a preliminary heating tube having a $\textcircled{?}$ shaped run of tubing a perforated burner shell supported by such run of tubing about the same, and a burner supported on the 130

lower end of such ? shaped run of tubing and arranged to project a stream of fuel oil into the burner shell against the convoluted portion of the ? shaped run of tubing.

5 8. In a fire-pot, the combination of a grid, a preliminary heating tube supported below the grid and having a portion shaped into a ? shaped run of tubing a perforated burner shell having a laterally-extended lip and 10 means for clamping the lip to the upper end of the ? shaped run of tubing, and a burner supported on the lower end of the ? shaped run of tube and arranged to project a stream of fuel oil up against the shell and against 15 the convoluted portion of the ? shaped run of tubing.

9. In a fire-pot, the combination of a grid, a preliminary heating tube supported below the grid and having a portion arranged 20 in a ? shaped run of tubing, a perforated burner shell having a laterally-extending lip arranged to seat upon the upper portion of the ? shaped run of tubing and having an out-dented side arranged to seat the

lower run of the ? shaped run of tubing, 25 and a burner secured to the lower end of the said run of tubing and arranged to direct a stream of fuel oil up against the convoluted portion of the ? shaped run of tubing.

10. In a fire-pot, the combination of a 30 ring-like grid having a stationary section and a hinged section, a tank, a plurality of posts for supporting the stationary grid section upon the tank, the hinged section having a downwardly offset portion pivotally supported upon one of the posts and a second downwardly offset portion at the free end with a hook-like arrangement for swinging over the adjacent post, a nut on such post for tightening up against the hook portion of the swinging grid section, and an oil pipe and preliminary heating tube having a detachable coupling arrangement with the tank and which can be lifted out of the grid when the hinging section is open. 40 45

In testimony whereof I affix my signature.

FREDERICK L. LINDHORST.
